ATTORNEY

UNITED STATES PATENT OFFICE.

JULIUS CARLSON, OF BROOKLYN, NEW YORK.

CAP.

Application filed December 22, 1926. Serial No. 156,386.

This invention relates to headwear, and is particularly applicable to caps.

Caps wherein a sweat-band is provided to encircle the entire head are now proving to be popular, and are frequently provided in caps of good quality. Such a sweat-band has not previously been applied to an adjustable cap without the use of elastic or similar means for taking up the slack in the sweatband or for tensioning the band to properly position the sweatband when adjustment of the size of the cap is made.

My invention contemplates the provision of a simple full sweatband adapted for use in adjustable caps, without the necessity for the use therewith of other means such as elastic and which comfortably fits the head of the wearer without pleats or wrinkles.

The various objects of my invention will be clear from the description which follows and from the drawings, in which,

Fig. 1 is a bottom plan view of a cap, showing my improved adjustable sweatband.

Fig. 2 is a side view of a part of the outside of an adjustable cap, part of the lower portion of the cap being shown removed to expose the sweatband.

Fig. 3 is a side view of a part of the inside of an adjustable cap, showing particularly my improved sweatband.

It is desirable in adjustable caps, to have a sweatband extending entirely about the lower edge of the head opening. In that practical embodiment of my invention illustrated I provide such a sweatband by forming said band in two unconnected sections. The front section 25 is secured to the vizor 17 in the usual manner, while the rear section 26 is also secured to the lower edge of 40 the crown in the usual manner, each of said sections extending substantially half way around the edge of the head opening in the cap, and meeting at the sides of the cap.

Near the points where the sweatband sections meet, the crown is slit as at 27 for a distance sufficient to allow the lowermost edge of the cap to be shortened and lengthened to accommodate heads differing in size. On the front side 33 of the slit 27, the lowest edge of the crown is provided with a tongue or extention 28 preferably of the same material as the cloth of the cap. To the inside of said tongue is secured the prolonged end 29 of the front sweatband sec-

tion 25 as by means of suitable stitching 32, whereby the tongue is sufficiently stiffened to effect its purpose of preventing collapse of the cap at the slits, without the necessity for the use of additional stiffening material. The end 29 projects rearwardly past the rear end of the vizor and is unsecured thereto.

At each of the forward ends 30 of the rear sweatband section 26, a slot as 31 is made, into which the joined tongues 28 and 29 are inserted for free movement therein. The height of the slot 31 being slightly greater than that of the said tongues, little or no resistance is offered to the adjusting movement when the band sections 25 and 26 are moved together or further apart. The tongues 28 and 29 pass through the slot 31 and are hidden by and behind the sweatband section 26, but as hereinbefore pointed out, are free to move unconstrainedly in said slot 75 when the adjustment of the cap is effected. When the size of the cap is increased, the tongues are pulled further out of the slots by the action of the head of the wearer at the time the cap is put on. The same effect 80 may be obtained merely by giving the cap a quick snap or jerk without necessarily touching the sweatband at all. When the size of the cap is decreased, the constricting pressure on the sweatband caused by the adjusting straps forces the tongues further into the slots 31, without the aid of any other means.

It will be seen that I have provided an efficient full sweatband particularly adapted for use in adjustable caps. Various modifications are contemplated, and may be made, of the preferred specific embodiment of my invention shown and described, since that embodiment is intended to be illustrative 90 only. I do not therefore intend to limit myself solely to the construction so illustrated, but intend that modifications including the equivalents falling within the range of the appended claims be included herein. 100

I claim:

1. In an adjustable cap, having side slits therein, a rear sweatband section of a single thickness of material secured in place and terminating at the sides of said cap and having slots therein near the ends thereof, a front sweatband section of a single thickness of material secured to the front part of said

cap, a tongue on the end of said front section extending past the side slits in said cap and having its rear end free to enter and to be removed from the slot of said rear section, 5 and a tongue on the cap projecting from the front side of the slit rearwardly of said slit and seamed to the tongue of said front section and having its rear end similarly free, whereby said tongues are unconstrainedly 10 movable circumferentially in said slot.

2. In an adjustable cap having side slits therein; a two-piece sweatband each of a single thickness of material and completely separable into two pieces and having ends in 15 freely movable interengagement at said side slits, and projecting tongues on the front part of said cap at said slits seamed to the ends of one piece of said sweatband whereby the lower edge of the front of said cap is 20 movable with the front piece of the sweatband relatively to the rear part of the cap.

3. In an adjustable cap, a finished front sweatband section of a single thickness of material secured at the front part of the edge of the head opening of said cap, a finished rear sweatband section of a single thickness of material secured at the rear part of said edge and having a slot therein, means for adjusting the head size of said cap and for restraining said rear section whereby 25 tension is put upon said rear section when the cap is worn, and a rearwardly projecting tongue on said cap and a similar tongue on the end of said front section said tongues being secured together and inserted into the 30 slot of said rear section and passing between said rear section and the material of said cap, whereby said tongues are at all times free to move circumferentially in said slot on the tensioning or compressing of said sweat- 40 band.

JULIUS CARLSON.
